UNITED STATES PATENT OFFICE.

MARTIN VAN BUREN, OF DAYTON, WASHINGTON.

CARPET-BEATING MACHINE.

Application filed May 23, 1921. Serial No. 471,749.

To all whom it may concern:

Be it known that I, MARTIN VAN BUREN, a citizen of the United States, residing at Dayton, in the county of Columbia and 5 State of Washington, have invented new and useful Improvements in Carpet-Beating Machines, of which the following is a specification.

This invention relates to a machine for 10 beating carpets and the like, the general object of the invention being to provide a power driven device including a set of beaters for striking the carpet a series of blows, the effect being somewhat similar to that secured by beating the carpet with a stick or 15 the like.

Another object of the invention is to provide a rotary member, actuated by a motor, with projections thereon for engaging the 20 spring beaters for raising them against the spring action.

This invention also consists in certain other features of construction and in the combination and arrangement of the several 25 parts, to be hereinafter fully described, illustrated in the accompanying drawings and specifically pointed out in the appended claim.

In describing my invention in detail, reference will be had to the accompanying 30 drawings wherein like characters denote like or corresponding parts throughout the several views and in which:—

Figure 1 is a side view of the invention.

Figure 2 is a plan view.

Figure 3 is a section on line 3—3 of Figure 2.

Figure 4 is a section on line 4—4 of Figure 2.

Figure 5 is a detail view.

Figure 6 is a view showing the device combined with a vacuum cleaner.

Figure 7 is a view showing the device covered by a hood.

Figures 8, 9 are detail views of the means for attaching the vacuum cleaner to the device and of the hood parts.

In these views 1 indicates the frame which is secured to the axle 2 which carries the 50 wheels 3. A handle 4 is adjustably secured to the frame by means of the bolt 5. A motor 6 is placed upon the frame and the wires therefrom pass through the handle and are connected with a suitable switch 7 located in the handle. A pair of beaters 8 is secured to the frame, each beater being

formed of wire looped upon itself and having its ends suitably secured to a part of the frame, said ends being spirally wound to form springs 9, these springs holding the 60 beaters against a part of the frame. A disc 10 is rotatably mounted in the frame between the beaters and said disc carries a series of pins 11 for engaging projections 12 on the beaters for lifting said beaters upwardly off the frame against the spring action. The periphery of the disc is provided with teeth and the shaft of the motor is provided with a gear 13 which meshes with said teeth so that the disc will be rotated when 70 the motor is in operation.

It will thus be seen that the beaters will be raised when the disc is being rotated by the motor and as the pins leave the projections 12 the springs 9 will cause the beaters to snap back into their original position so that the looped parts will strike the carpet a sharp blow. Thus the carpet will be effectually cleaned of dust and dirt.

The carpet can be placed on the ground or 80 upon springs such as bed springs while being operated upon. The wheeled frame with the handle permits the device to be moved over the carpet so that all parts thereof can be beaten.

I may provide a screw controlled slide 14 for controlling the blows of each beater.

My device can also be used in the house for beating the carpets while upon the floor. When this is done I prefer to combine with 90 the device an ordinary vacuum cleaner, such as shown at 15, and the entire device is covered by a hood 16 for confining the dust. The vacuum cleaner is connected with the device by the brackets 17, the dust bag of the cleaner being attached to the handle of the device. The hood 16 comprises a wire frame 18 which has loops 19 at one end for engaging grooves 20 in the nuts 21 which secure the wheels to the axle. A strip 22 is secured to the front end of the frame and carries a roller 23 for supporting the said front end. A cover 24 fits over the frame and extends to the floor. I also prefer to cover the beaters with cloth or the like, as 95 shown at 25.

It will thus be seen that the device can be used for cleaning carpets while lying upon the floors and the dust and dirt beaten out of the carpets will be taken up by the vacuum 110 cleaner, the hood preventing the dust and dirt from escaping into the room.

By raising the handle the blows of the beaters can be regulated as by lowering the handle the beaters will not strike the carpet with such force as they will strike it near the end of their stroke while by raising the handle they will strike the carpet heavier blows.

It is thought from the foregoing description that the advantages and novel features 10 of my invention will be readily apparent.

I desire it to be understood that I may make changes in the construction and in the combination and arrangement of the several parts, provided that such changes fall within 15 in the scope of the appended claim.

What I claim is:—

A carpet beating machine of the class described comprising a wheeled frame, a handle adjustably secured to said frame and

a motor rotatably mounted upon the frame, 20 a pair of beaters secured upon the frame which are formed of wire looped upon itself and having its ends secured to a part of the frame and spirally wound thereon to provide springs which are adapted to hold the 25 beaters against a part of the frame, a rotatable disc mounted in the frame between the beaters, a series of pins carried by said disc and adapted to engage projections provided on the beaters, said disc having teeth provided on the periphery thereof and a gear provided on the shaft of a motor which is adapted to mesh with said teeth for rotating the disc upon rotation of the motor.

In testimony whereof I affix my signature.

MARTIN VAN BUREN.
